INVENTOR.

A.R. Griesemer

BY *George D. Webster*

ATTORNEY

UNITED STATES PATENT OFFICE.

ABRAHAM R. GRIESEMER, OF SAN FRANCISCO, CALIFORNIA.

WATER-PRESSURE EJECTOR.

Application filed July 5, 1923. Serial No. 649,530.

To all whom it may concern:

Be it known that I, ABRAHAM R. GRIESEMER, a citizen of the United States, residing at San Francisco, county of San Francisco, State of California, have invented certain new and useful Improvements in Water Pressure Ejectors; and I do declare the following to be a full, clear, and exact description of the same, reference being had 10 to the accompanying drawings, and to the characters of reference marked thereon, which form a part of this application.

This invention relates to improvements in under-water dredging or excavating devices, 15 and especially to a type particularly adapted and intended for sinking holes in the beds of streams, and bodies of water generally, for removing dirt from around piles, piers, etc. and in general for use in excavating small 20 areas at a time, in any place where the material being worked on consists of sand, mud, gravel or any more or less finely divided material.

My present device has all the advantages 25 of operation had with the ejector described and featured in Patent No. 1,459,153 granted to me June 19th, 1923, with however certain improvements in construction, the advantages of which are manifested in a lessened expense for the necessary accompanying 30 accessories or equipment, and also with a lower operating cost.

The above advantages are obtained by constructing the ejector so that both the excavating and loosening of the solid material, and the raising of the same to the surface is done by means of a continuous circulation of water under pressure alone, instead of with the aid of an air blast as in 40 the previous device, and to provide a device so constructed that this method of operation may be successfully carried out forms the principal object of the present invention.

45 A further object of the invention is to produce a simple and inexpensive device and yet one which will be exceedingly effective for the purposes for which it is designed.

50 These objects I accomplish by means of such structure and relative arrangement of parts as will fully appear by a perusal of the following specification and claims.

In the drawings similar characters of reference indicate corresponding parts in the 55 several views:

Fig. 1 is a side elevation of the device.

Fig. 2 is a vertical section, and

Fig. 3 is a top plan view.

Referring now more particularly to the 60 characters of reference on the drawings, the numeral 1 denotes a body of suitable size and exterior form having attached to its upper end incoming and discharge pipes 2 and 3 respectively, made of a strength sufficient to withstand heavy water pressures, the pipe 2 being somewhat larger than pipe 65 3.

The pipe 2 leads primarily to a substantially bowl-shaped chamber 4 formed in the 70 body. The pipe 3 communicates with a vertical discharge chamber or passage 5 extending to the bottom of the body. Leading from the chamber 4 to the passage 5 and terminating in an upwardly projecting tip of 75 reduced size is a passage or jet member 6, formed integral with the body, and designed to discharge straight up into the passage 5 and pipe 3 and yet not choke said passage 80 to any detrimental extent.

Projecting below the body directly under the chamber and communicating therewith is a Y-bend or lateral pipe fitting 7 at whose lower end is mounted a nozzle 8 provided with openings 9 set at suitable opposed 85 angles to the vertical axis of the nozzle and body, the nozzle being removable so that the type of nozzle used may suit the material being worked on.

Attached to the side of the fitting is a jet 90 pipe 10 whose outer end projects upwardly in vertical alinement with the axis of the passage 5 and which terminates a certain distance below the lower end of said passage. This jet being preferably of smaller 95 size than the passage 11 leading from the chamber 4 to the fitting 7. Similarly the combined area of the nozzle holes is less than that of the passage 11, so that neither the jet nor the nozzle will alone take all the 100 water entering the fitting through said passage.

In operation, a continuous stream of water under pressure, provided by a force pump or otherwise, is forced down the pipe 105 2. The volume of water thus supplied to

the chamber 4 then leaves the same through the jets 6 and 10, and also through the nozzle.

The jet 6 discharging directly into the passage 5 and discharge pipe 3, creates an upward flow of water in the latter, which of course exerts a tendency to draw further water into the passage 5 below said jet. This tendency or automatically induced upward current in the lower portion of the passage 5 is aided by the upward discharge from the lower jet 10, which acts on the water thereabout and induces an upward current from therebelow.

Meanwhile the water issuing forcibly from the nozzle 8 loosens and stirs up the material against which the nozzle is directed, and said loosened material is drawn toward and mingled with the upward current flowing into the passage 5, and of course passes then upwardly through the pipe 2 to be ultimately discharged at any desired point.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A hydraulic lift apparatus including a pressure feed pipe and a lift pipe, the latter being of smaller cross sectional area than the former, a terminal common to both, the lift pipe being freely open through the terminal, and the feed pipe having an elbow within the terminal having a restricted discharge outlet upwardly into the lift pipe whereby hydraulic pressure from the feed pipe will provide a lifting force within the lift pipe, a discharge pipe connected with the terminal and communicating with the feed pipe, such discharge pipe having two outlets, one directly downward to agitate the material to be lifted and the other curving upward into alignment with but below the open end of the lift pipe to maintain a constant current theretoward to keep the agitated material flowing thereto instead of being dissipated therefrom by the force of the water from the agitating discharge nozzle.

2. A hydraulic excavator comprising sep-

arate pressure and discharge chambers, the latter being freely open at its lower end, a jet from the pressure chamber discharging upwardly into the discharge chamber, another jet connected with the pressure chamber and discharging upwardly toward the discharge chamber but positioned below the same, and a downwardly facing nozzle connected to the pressure chamber and positioned in a plane below the discharge chamber.

3. In a dredging apparatus, the combination of a pressure feed pipe and a lift pipe, the former being of greater area than the latter, and a plurality of outlets from the feed pipe, whereby fluid under pressure may be directed therethrough to agitate and drive the dredged material into the lift pipe.

4. In a dredging apparatus, the combination of a pressure feed pipe and a lift pipe, the latter being open at its lower end, a passage from the feed pipe directly into the lift pipe and facing upwardly in the latter, a discharge pipe from the lower end of the feed pipe, such a pipe having two outlets, one directed downward and the other upwardly toward the lower open end of the lift pipe.

5. In a dredging apparatus, the combination of a pressure feed pipe and a lift pipe, the latter being open at its lower end, a passage from the feed pipe directly into the lift pipe and facing upwardly in the latter, whereby some of the fluid under pressure in the feed pipe will be forced upwardly in the lift pipe, and jet means mounted in connection with the feed pipe and arranged to agitate the matter to be dredged and to cause such agitated matter to be directed up into the lift pipe into the sphere of influence of the flow of fluid issuing into the lift pipe from the passage.

6. In a dredging apparatus, the combination of a pressure feed pipe and a lift pipe, the latter being open at its lower end, a passage from the feed pipe directly into the lift pipe and facing upwardly in the latter, whereby some of the fluid under pressure in the feed pipe will be forced upwardly in the lift pipe, and jet means mounted in connection with the feed pipe and arranged to cause any matter in suspension adjacent the lower open end of the lift pipe to be directed up into the same and into the fluid issuing into the lift pipe from the passage.

In testimony whereof I affix my signature.

ABRAHAM R. GRIESEMER.
